UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A PORTABLE BASKET-GRADE.

SPECIFICATION forming part of Design No. 36,050, dated September 9, 1902.

Application filed July 29, 1902. Serial No. 117,570. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Portable Basket-Grates, of which the following is a full, clear, and exact description, reference being had to the accompanying drawing, forming part hereof, in which the invention is represented in perspective view.

The leading features of my design consist of corner-pieces each having an ornamentation on its front face somewhat representing the conventional sunburst. Extending from the tops of the corner-pieces are standards terminating in inwardly-turned volute or scroll work, the standards being connected by a series of cross-bars. Extending rearwardly from about the level of the lower cross-bar and of about the length thereof is a grate-

plate of any conventional form. Extending between the corner-pieces and in width about the height of the corner-pieces is an open-work portion having a central sunburst ornamentation, and extending therefrom on each side are two rows of conventional scrolls oppositely directed and facing the center piece. The top and bottom of the open-work portion and of the corner-pieces have a bead-like ornamentation.

I claim—

The ornamental design for a portable basket-grate as herein shown and described.

In testimony whereof I have hereunto set my hand in the presence of two subscribing witnesses.

THOMAS M. DUDGEON.
